UNITED STATES PATENT OFFICE.

CARL A. WITHAM, OF MINNEAPOLIS, MINNESOTA.

BAG OF PAPER OR OTHER FLEXIBLE MATERIAL.

Application filed November 12, 1926. Serial No. 147,915.

My invention relates to bags of paper or other flexible material. An object is to provide a bag of such material having a restricted pouring opening or mouth so that the contents of the bag may be poured without danger of spilling. It is, of course, old to provide containers of rigid material with restricted pouring mouths but so far as I am aware it has not been customary to provide bags or sacks of flexible material with such mouths. Bags of this kind when manufactured are commonly left open at the top for the complete cross section of the bag with the result that it is almost impossible to pour out the contents without spilling some of it. This is particularly noticeable in the case of bags employed for holding popcorn, candy, breakfast foods, and various materials of a more or less granular or pulverulent nature which are commonly poured out of the bag, a portion at a time. A further object is to provide a bag having a restricted pouring mouth having a tendency to remain closed but which may be readily opened by a squeezing action so that the contents may be readily poured.

The full objects and advantages of my invention will appear in connection with the detailed description thereof, and the novel features of my inventive idea will be particularly pointed out in the claims.

In the accompanying drawings which illustrate a practical embodiment of my invention—

Fig. 1 is a perspective view showing a completed bag in collapsed condition. Fig. 2 is a perspective view showing the bag in expanded condition and with the mouth open for pouring therefrom. Fig. 3 is a perspective view showing the upper portion of the bag creased and ready to be folded to complete the bag. Fig. 4 is a perspective view showing the creased portions partly folded over. Fig. 5 is a front elevational view of the bag in the partly completed condition shown in Fig. 4.

The drawings show my improved bag as being made from a customary form of collapsible paper bag which has longitudinal creases 10 midway along two of its opposite sides, these creases leading into inclined

creases 12 near the bottom so that the bag may be made to assume a flat condition as shown in Fig. 1 by folding over the bottom member 14. The manner in which the top portion of the bag is manipulated to produce the improved bag will be understood by referring particularly to Fig. 3. A portion of the material at the top is cut away so as to leave a tongue 16 projecting from one of the uncreased sides of the bag, it being noted that the two uncreased sides are shown as wider than the two creased sides. The other uncreased side is cut so as to provide a tongue 18 which is somewhat longer than the tongue 16. Instead of cutting the tongue 18 entirely free, a strap 20 is left projecting from one side thereof. At the four upper corners, the material is folded on pairs of inclined lines 22, the pairs of lines being so arranged that the two lines of a pair meet each other at the points 24 located a fraction of the distance from the top to the bottom of the bag. Triangular portions 26 are thus produced which are pasted or otherwise secured. This decreases the cross section of the bag at the top. The strap 20 is pasted around the two tongues so that a restricted mouth for the bag is completed as will be apparent from Fig. 2. On account of the tongues 16 and 18 being encircled by the strap 20, which is secured to the outside thereof, the mouth tends to remain practically closed as shown in Fig. 1 but by applying a slight pressure at the two opposite sides, the mouth is made to assume the open position shown in Fig. 2 so that the contents may be readily poured out without liability of being spilled. The fact that the tongue 18 is longer than the tongue 16 aids in the pouring operation when the bag is held with the longer tongue 18 on the lower side. If desired, the excess portion of the tongue 18 may be folded over and secured thereby producing a complete seal for the bag.

I claim:

1. A bag of paper or other flexible material having vertical sides manipulated at the upper end of the bag to reduce the cross section thereof; oppositely disposed tongues extending up from said reduced portion, and a straplike piece of material secured around

said tongues to produce a single restricted opening.

2. A bag of paper or other flexible material having vertical sides extending from the bottom to a place near the top, tongues extending up from opposite sides, the material at the four upper corners being folded

to reduce the cross-section of the bag at the base of the tongues, and a straplike piece of material secured around said tongues to produce a restricted pouring opening.

In testimony whereof I hereunto affix my signature.

CARL A. WITHAM.
